UNITED STATES PATENT OFFICE

EMIL SWANSON, OF STEGER, ILLINOIS, ASSIGNOR TO STEGER & SONS PIANO MANUFACTURING COMPANY, OF STEGER, ILLINOIS.

PNEUMATIC ACTION FOR AUTOMATIC PLAYING MECHANISM.

1,079,072.

Specification of Letters Patent.

Patented Nov. 18, 1913.

Application filed January 8, 1913. Serial No. 740,769.

To all whom it may concern:

Be it known that I, EMIL SWANSON, a citizen of the United States, residing at Steger, in the county of Will and State of Illinois, have invented new and useful Improvements in Pneumatic Actions for Automatic Playing Mechanism, of which the following is a specification, reference being had to the accompanying drawings, forming a part thereof.

The purpose of this invention is to provide an improved construction of the pneumatic action of an automatic playing mechanism or keyed instrument.

It consists in the elements and features of construction shown and described as indicated in the claim.

In the drawings: Figure 1 is a vertical fore-and-aft section of a pneumatic action embodying this invention, the same being shown in connection with the hammer action of the piano on which it operates. Fig. 2 is a detail axial section of a primary pneumatic valve involved in the structure.

The pneumatic action embodying this invention is shown in connection with the hammer action of a piano upon which it operates, comprising the wippen, 1, and the back-check, 2. The manual key, 3, and abstract, 4, are also shown to indicate the relative position of the pneumatic action with respect to the manual. The power pneumatics, 5, of this pneumatic action are positioned vertically with their moving members, 6, hinged at the upper end and the lower end of each connected by rods, 5^a, with the vertical depending arm, 8, of a bell crank lever, 8, 9, fulcrumed at its angle and having its horizontal arm, 9, operating upon the wippen. The power pneumatics, 5, in two rows are mounted upon the exhaust chambers, 10, 10, positioned one behind the other, the power pneumatics being thus comprised in two rows, the pneumatics of each row being opposite the intervals between the pneumatics of the other row in the usual staggered arrangement. Each power pneumatic is controlled by a secondary pneumatic, 12, operating the valve, 13, the secondary pneumatic being in turn controlled by a primary pneumatic, 14, operating the double valve device, 15, the primary pneumatic being controlled in the usual manner by the admission of air through the duct, 16, leading from the tracker, (not shown).

With the power pneumatics and their connections arranged as above described, it will be observed that all parts connected, including the wippen with its hammer and the bell-crank lever, 8,—9, operate by gravity to hold the power pneumatic in expanded position, supplementing the natural reaction of the bellows element of the power pneumatic for this purpose; and, in view of the suspended position of the moving member, 6, making it require but very slight force to move it from collapsed to expanded position, this arrangement of the parts contributes to very easy action of the power pneumatic, making it possible to dispense with expanding springs or equivalent devices and so reducing to a minimum the force necessary for the collapsing action.

In order to render the stroke of each power pneumatic exact and exactly adapted to the action of the particular hammer upon which it operates, there is set through the moving wall of each power pneumatic a stop device comprising a screw-eye with a threaded stem, 18, and an exterior eye serving as the means of manual operation; the stem has on its inner end a button, 19, which may be adjusted by screwing the stem through the moving wall so as to protrude more or less from the inner surface of the moving wall, 6, for encounter with the fixed wall to limit the collapse of the pneumatic. In order that the range of stroke of the pneumatic may not be restricted by the presence of the button, 19, the inner surface of the moving wall, 6, is formed with a pocket, 6^a, deep enough to receive half the button and the inner surface of the fixed wall, 7, is provided with a similar pocket, 7^a, which accommodates the remainder of the thickness of the button. For limiting the recoil or expanding stroke of the pneumatic so as to prevent any loss of motion in the connections with the hammer action, there is suspended from the lower end of the forward pneumatic chamber by means of screws, 20, extended through spacing sleeves, 21, a bar, 22, through which there are set stop devices, 18,—19, identical in character with those above described, against whose buttons, 19, the moving walls of the rear set of motor pneumatics are stopped in their expanding movement. From the lower end of the same exhaust chamber, brackets 23,—23, extend forwardly past the forward

row of power pneumatics for supporting a stop bar, 24, against which the moving walls of the forward set of pneumatics are stopped.

- 5 The primary pneumatic valve device comprises a stem, 25, which is threaded for its whole length from its foot flange, 26, to the end, a spacing sleeve, 27, which is screwed onto its stem between the two valves, 28,—28,
10 having their flat seating faces toward each other for seating at opposite ends of the port, 29, which they control, said seating faces being covered as usual with leather for insuring air-tight seating. The con-
tinuity of the thread and the stem, and the threading of the three elements,—namely,
15 the sleeve and the two valves,—onto the stem adapts the device for adjustment of the two valves and the intervening spacer
20 bodily with respect to the foot flange to insure the proper action of the pneumatic, 14, upon which the foot flange seats and by which the valve is operated for seating upwardly upon the inflation of said pneumatic,
25 the vertical position of the valves causing them to act by gravity for seating in the

opposite direction when the air compression is balanced upon opposite sides of the pneumatic, 14.

I claim:

30 In a pneumatic action for automatic playing devices, in combination with a plurality of exhaust chambers mounted one behind the other above the manual keys; power pneumatics mounted upon the vertical walls of said exhaust chambers, respectively, having their moving members hinged at the upper end; connections from the lower end of said walls for operating the sounding devices; stop bars suspended from the lower 35 end of the forward exhaust chamber extending in front of the lower ends of the two sets of power pneumatics, respectively, and stops for the respective power pneumatics mounted on said bars.

40 In testimony whereof, I have hereunto set my hand at Steger, Illinois, this 7th day of December, 1912.

45 EMIL SWANSON.
